UNITED STATES PATENT OFFICE.

GEORGE S. GRUBER, OF SCOTIA, NEW YORK.

OILSTONE BOX.

Application filed February 3, 1926. Serial No. 85,769.

My present invention has reference to a box or a holder for oil stones, such as are commonly employed by carpenters, cabinet makers and the like for sharpening edge 5 tools.

An object of the invention is the provision of a box for this purpose having a cover in the nature of an oil well or receptacle normally closed by a spring influenced valve 10 which latter is opened by pressure against and the flexure of the top of the cover, so that a sufficient quantity of oil may be conveniently fed to the stone and the employment of an oil can for this purpose entirely 15 overcome.

A still further object is the provision of an oil-stone box in which the stone is firmly held but is susceptible to swinging and tilting laterally so that either of its faces may 20 be arranged in grinding position.

With the above broadly stated objects in view, and many others which will present themselves as the nature of the invention is better understood, the improvement further 25 resides in certain other novel features of construction, combination and operative association of parts, a satisfactory embodiment of which is illustrated by the accompanying drawings.

30 In the drawings:

Figure 1 is an approximately central longitudinal sectional view through my improvement, the oil stone being in elevation.

Figure 2 is a sectional view approximately 35 on the line 2—2 of Figure 1.

Figure 3 is a detail sectional view approximately on the line 3—3 of Figure 1.

Figure 4 is a fragmentary sectional view approximately on the line 4—4 of Figure 2.

40 Mechanics having use for oil stones for sharpening edge tools are well acquainted with the inconvenience of applying oil in the usual method. In the first place, the oil can is seldom conveniently located, and in the 45 second place the cover for the box seldom excludes dust from the stone and in the third place great inconvenience is occasioned in removing the stone from the pocket in the box so that the grinding face thereof can be reversed. My improvement aims to obviate all of these inconveniences. The base or box proper may be, and preferably is constructed of wood. This base is indicated in the drawings by the numeral 1. 50 The base is centrally formed with a substantially rectangular pocket 2 for the oil stone

3. The sides and ends of the base, opposite the end of the pocket are channeled or cut-away to provide a continuous horizontal ledge 4 and a continuous upstanding flange 60 5. It is, of course, to be understood that the base or box is of rectangular formation. On one of the inner faces of the end flange 5 there is journaled in suitable bearings a rod or bar 6. Centrally connected to this 65 bar there is a pivot member 7. The pivot has both of its ends headed and is preferably surrounded by a sleeve 8 that spaces a yoke-like clamp 9 from the bar or plate 6. The yoke-like clamp 9 is connected to the 70 pivot 7, and the spring arms 10 of the yoke may be received in depressions 11 in the sides and one end of the oil stone 3. However, this is not an absolute requirement, as one end of the oil stone may be fully received within the yoke and held therein in 75 frictional engagement with the arms 10 at the sides of the said stone. The opposite end flange of the box 1 may have its inner face cut at a slight angle so that the stone 80 may be swung out of its pocket 2 about the axis of the bar 6 and then turned on the pivot 7 to bring the second face of the stone into grinding position. The advantage of 85 this arrangement will be apparent to those having use for such devices.

The cover 12 is in the nature of a cap-like member and is preferably constructed of metal which, of course, embodies a natural resiliency. The edges of the cover are 90 rolled, as at 13, to provide open beads, and these beads rest upon the ledges 4 while the inner faces of the side and end flanges of the cover frictionally engage with the continuous flange 5 of the box 1. Arranged in 95 the cover 12, at a suitable distance from the top thereof, there is a partition 14. By reference to Figures 1 and 2 of the drawings, it will be noted that the partition is arranged in the cover a suitable distance above 100 the stone 3, so that the resiliency of the lower sides and ends of the cover is not impaired and also that the said partition does not contact with the stone.

The partition may be of any desired 105 material and the same is, on its outer face, centrally enlarged and provided with a threaded opening. In this opening there is screwed a cap nut 15. The top of the cap nut has a central opening therethrough for 110 the reception of the stem 16 of a valve 17. The valve, on its inner face, has a compres-

sible face 18, and the stem 16 has on its outer end a head 19. On the stem and exerting a pressure between the head 19 and the cap nut 15, there is a helical spring 20 which 5 holds the valve closed.

The head 19 is disposed close to the top of the cap 12. The user of the device is, of course, acquainted with the position of the head 19, and by exerting a pressure upon the 10 top of the cap to flex the same inwardly, a like pressure will be exerted upon the head 19, which will move the stem 16 to unseat the valve 17; and thus emit a sufficient quantity of oil, (which, it should be stated, is received 15 in the compartment between the top and the partition 14 of the cover), to allow a determined quantity of such oil flowing onto the stone. Thus the stone is oiled before the cap is removed from the box. The supply 20 of the oil is replenished by opening the valve and employing the cap nut 15 as a funnel to allow the said oil to pass through the rather large opening in the cap nut that provides the guide for the stem 16.

25 The simplicity of my construction and the advantages thereof, will it is believed, be

perfectly apparent to those skilled in the art to which this invention relates, when the foregoing description has been carefully read in connection with the accompanying 30 drawings. It is, of course, to be understood that I do not wish to be restricted to the precise details herein set forth and may make such changes therefrom as fairly fall within the scope of what I claim. 35

Having described the invention, I claim:—

The combination with an oil stone box and an oil stone therein, of a yoke-like spring clamp whose arms frictionally engage with the sides of the oil stone, a central pivot 40 extending from the clamp and a bar having its ends rotatably journaled in bearings on one of the inner ends of the box and to which the pivot is connected, the wall of the box opposite said bar being cut away at an angle 45 to permit the swinging of the stone out of the box about the bar as an axis and its swiveling about the central pivot to reversely position the stone.

In testimony whereof I affix my signature.

GEORGE S. GRUBER.
